UNITED STATES PATENT OFFICE

2,573,116

BLOCK FOR INTERNAL-COMBUSTION ENGINES

Felix J. Stuckert, Wauwatosa, Wis., assignor to
 Briggs & Stratton Corporation, Milwaukee,
 Wis., a corporation of Delaware

Application November 6, 1947, Serial No. 784,408

1 Claim. (Cl. 123—195)

1

This invention relates to internal combustion engines and has more particular reference to engine blocks of die cast construction.

Because of the advantage of lightweight construction, the manufacture of internal combustion engines using aluminum die castings for the block is becoming more and more popular. Although aluminum die castings are desirably light in weight, the metal is relatively soft and incapable of withstanding the wear incidental to the operation of such elements of the engine as valves and pistons, and it is customary to embed inserts, usually of cast iron, into the die cast blocks to slidably receive these parts and to seat the valves of the engine.

At present these inserts are separately embedded in the block at the time of die casting the same; it being understood, of course, that the inserts are held in a predetermined position relative to one another during the die casting operation.

While the inserts thus commonly employed have the ability to withstand considerable wear and afford excellent bearing and valve seating surfaces, engine blocks having such inserts have been found unsatisfactory by reason of the fact that the inserts have a different coefficient of expansion than the aluminum or other die cast metal from which the block is made; and this differential in expansion made it impossible to maintain a predetermined dimensional relationship between the inserts over the entire range of operating temperatures of the engine. In many instances the differential of expansion between the inserts and the die cast metal resulted in loosening of the inserts to a degree such as to seriously impair the operation of the engine.

With these objections in mind it is an object of the present invention to provide a die cast block for internal combustion engines having inserts of unitary design embedded in the die cast metal so as to assure the maintenance of a predetermined dimensional relationship between the components of the inserts.

More specifically it is an object of this invention to provide a die cast block for internal combustion engines with a combination valve and piston insert of unitary construction embedded in the die cast metal.

With the above and other objects in view, which will appear as the description proceeds, this invention resides in the novel construction, combination and arrangement of parts substantially as hereinafter described and more particularly defined by the appended claim, it being under-

2

stood that such changes in the precise embodiment of the herein disclosed invention may be made as come within the scope of the claim.

The accompanying drawings illustrate two complete examples of the physical embodiment of the invention constructed according to the best modes so far devised for the practical application of the principles thereof, and in which:

Figure 1 is a side elevational view of a small 10 single cylinder internal combustion engine of die cast construction with portions of the block broken away to show the application of this invention thereto;

Figure 2 is a plan view of the block per se illustrating the unitary insert of this invention embedded therein;

Figure 3 is a fragmentary sectional view 15 through both valve seats taken along the plane of the line 3—3 of Figure 2;

Figure 4 is a fragmentary sectional view 20 through the intake valve seat taken along the plane of the line 4—4 of Figure 2;

Figure 5 is a fragmentary sectional view 25 through the exhaust valve seat taken along the plane of the line 5—5 of Figure 2;

Figure 6 is a plan view of a block similar to Figure 2 but illustrating a slightly modified insert in place in the block;

Figure 7 is a sectional view similar to Figure 30 5 taken through Figure 6 along the plane of the line 7—7; and

Figure 8 is a detail sectional view through a portion of the block taken along the plane of the lines 8—8 of Figure 6.

Referring now more particularly to the accompanying drawings wherein like numerals indicate like parts, the numeral 5 represents a single cylinder internal combustion engine of the air-cooled type having an upright block 6 of die cast aluminum, and a head 7 secured substantially flatwise upon the flat top surface 8 of the block. While the head 7 forms no part of this invention, it and the base for the block may also be aluminum die castings in keeping with the 40 lightweight construction of the engine.

The upper portion of the block at one side thereof is provided with a finned cylinder 9 to receive a piston (not shown) and as is usual the cylinder opens to the underside of the head 7 at the flat top surface 8 of the block.

It is to be understood that the block is provided with suitable valve operating mechanism (not shown) at the side of the block opposite the cylinder 9, including tappets adapted to be 50 housed within a chamber 10 alongside the cyl-

inder and closed by the usual detachable cover.

In accordance with this invention a single unitary insert 12 is embedded in the die cast metal of the block in the upper portions thereof, and this insert comprises a relatively flat plate 13 the top surface of which is flush with the surface 8 at the top of the block, a cylinder liner or sleeve 14 integrally joined with the plate and depending from its underside to define the bore of the cylinder, and valve mounts 15 and 16 for the intake and exhaust valves respectively. The valve mounts are likewise formed integrally with the plate 13 and extend downwardly therefrom alongside the cylinder liner.

Valve seats 17 are machined directly in the top surface of the plate and gas passages are provided in each of the valve mounts for the flow of fuel into the head and for the exhaust of burned gases from the head. In both valves the passages include an upright branch 19 beneath the valve seat and a lateral branch 20 extending at right angles from the lower portion of the upper branch. The lower branches 20 are substantially horizontal and open to the side of the block opposite the cylinder to provide for the introduction of fuel into the head and for the exhaust of burned fuel from the head as stated previously.

The stems of the engine valves are received in vertical bores 22 aligning with the valve seats 17, and these bores are machined in substantially cylindrical guide tubes 23 formed integral with the valve mounts and spaced a distance beneath the valve seats.

The insert 12 is preferably made of cast iron of a well known special type, as shown in Figures 1 to 5 inclusive, but the unitary aspect of the insert may also be attained by the construction illustrated in Figures 6 to 8 inclusive. In this latter instance the liner 14' is provided by a sleeve having its upper end fixed in a suitable aperture 25 in a steel plate 13' embedded in the top of the block to have its top surface flush with the top surface 8 of the block as previously described.

To insure rigidity of the joint between the sleeve 14' and the plate 13' the upper end of the sleeve may be turned down as indicated in Figure 7 for an axial distance corresponding to the thickness of the plate 13' and so as to provide a shoulder 26 on the sleeve which abuts against the underside of the plate. Although the reduced upper end portion of the sleeve 14' may be pressed into the aperture 25 of the plate, maximum rigidity is achieved by brazing or welding the sleeve to the plate at the joint 27 therebetween.

In this embodiment of the invention, the valve seats 17' are machined in the upper open ends of elbow-like inserts 28 carried by the plate at its underside as seen in Figure 7. The inserts 28 have their upright branch pressed into a suitable aperture 29 in the plate 13' and are likewise welded or brazed thereto at the joint 30 so as to assure absolute rigidity between the insert and the plate. The horizontal branch of the insert 28 leading from the bottom of the upright branch opens to the side of the block as shown in Figure 7, and if desired, a guide tube 31 of special steel alloy may be brazed or welded in an aperture in the bottom of the insert in line with the seat thereof.

In each of the embodiments shown the inserts are of ferrous metal, i. e. either steel or

a special cast iron, and the unitary nature of the inserts assures against the differential of expansion between the die cast metal and the inserts disrupting the dimensional relationship between the components of the insert and particularly between the valve seats and guides.

Referring again to the Figure 1 to 5 embodiment of the invention, it will be seen that the plate 13 forms but a small part of the top surface of the block, while the plate 13' of the Figure 6 embodiment provides substantially the entire top surface of the block with the exception of a relatively narrow annular rim at the extreme periphery of the block. In both instances, however, the plate is formed to have portions of the die cast metal extend thereover.

In the preferred embodiment the top surface of the plate 13 is stepped along its marginal edge as at 32 with the bottom of the step spaced beneath

20 the surface 8 of the block so as to enable the die cast metal to flow over the step during casting and thus anchor the plate firmly in place on the block. This condition is best illustrated in Figure 3. In the Figure 6 embodiment, relatively small areas 25 of the plate at the periphery thereof may be downwardly offset as indicated at 34 in Figure 8 so as to allow the die cast metal to overlie the offset portion for the purpose of securely anchoring the plate in place on the block.

30 From the foregoing description taken in connection with the accompanying drawings, it will be readily apparent to those skilled in the art that the unitary construction of the inserts of this invention assures rigidity between its component 35 parts to the end that the dimensional relationship between said components will be maintained throughout the entire range of operating temperatures of the engine.

What I claim as my invention is:

40 In a single cylinder internal combustion engine: a die cast block having a relatively upright cylinder which opens to the top of the block; a substantially rigid ferrous metal unit cast within the block, said unit including a plate-like member 45 having a flat upper surface forming substantially the entire top surface of the block, a cylinder liner joined to the plate-like member and extending downwardly therefrom into the block to define the inner wall of the cylinder bore, valve seats on the upper exposed surface of the plate-like member alongside the cylinder liner, valve guides joined to said plate-like member and extending downwardly therefrom in alignment with said valve seats, and marginal edge portions on the periphery of said plate-like member spaced inwardly from the sides of the block and offset below said top surface of the plate-like member and covered by the die cast metal of the block to securely anchor the ferrous metal unit in place 50 in the block; and a head detachably secured to the block at the top thereof and having a flat undersurface seating flatwise upon said flat top surface of the plate-like member.

FELIX J. STUCKERT.
